Primary Examiner — John Windmuller*Assistant Examiner* — Steven J Czyz(74) *Attorney, Agent, or Firm* — Armstrong Teasdale LLP(57) **CLAIM**

The ornamental design for a medication packaging combined with dispensing container, substantially as shown and described.

DESCRIPTION

FIGS. 1-8 are various views of a medication packaging combined with dispensing container in accordance with the present design. The container is adapted to contain a plurality of doses of medication therein.

FIG. 1 is a front perspective view of a medication packaging combined with dispensing container shown in a closed position;

FIG. 2 is a front elevation view thereof;

FIG. 3 is a rear elevation view thereof;

FIG. 4 is a right side elevational elevation view thereof;

FIG. 5 is a left side elevation view thereof;

FIG. 6 is a top view thereof;

FIG. 7 is a bottom view thereof; and,

FIG. 8 is a front perspective view of the medication packaging combined with dispensing container shown in an open position for ease of disclosure.

The broken lines depict portions of the article that form no part of the claimed design.
